SAMUEL CLAY BARR, OF CHILLICOTHE, OHIO.

07 **RESILIENT WHEEL.** **Specification of Letters Patent.** **Patented July 16, 1918.**
1,272,602.

Specification of Letters Patent. Patented July 16, 1918.

Application filed January 11, 1915. Serial No. 1,557.

an older brother is likely to

To all whom it may concern,

Be it known that I, SAMUEL CLAY BARR,
a citizen of the United States of America,
residing at Chillicothe, in the county of Ross
and State of Ohio, have invented certain
new and useful Improvements in Resilient
Wheels, of which the following is a specifi-
cation.

My invention relates to resilient wheels and comprises a novel type of wheel structure designed to conform as nearly as possible to the form of resilient wheel at present in use upon automobiles, and at the same time to provide a structure more durable and having a greater period of efficiency than the inner tube structure commonly used at the present time.

My improvement contemplates the provision of an annular formation having yielding tread members, and being preferably provided with a rigid, circular base upon which these tread members are yieldably mounted. This annular formation may be used with an outer shoe and practically serve as a substitute for the inner tube, or it may be used without any shoe and serve as the tread surface of the wheel. The lat-

text will probably be preferable in vehicles of a heavier nature. Various features of importance in my invention will appear as this description progresses. Similar characters of reference will indicate corresponding parts throughout the drawings appended to and forming a part

of this application. In these drawings, Figure 1 is a side elevation of my improved wheel structure partially broken away, showing a tilted hub to show Fig. 2 is a transverse section showing the manner of mounting my improvement upon the felly of the normal wheel. Fig. 3 is a detail showing one of my improved tread sections and supporting hinges.

Fig. 4 is a detail showing adjacent ends of two tread sections and the collapsible box-like formation which supports the said adjacent ends and permits them to yield independently of each other.

In the drawings, the wheel is shown as comprising a hub 1 with spokes 2 extending radially therefrom and carrying a felly 3 upon which are adjustably mounted clencher rings 4 and 5, arranged to clamp a non-metallic shoe 6 under stress of bolts 7 extending

My improved resilient member is preferably of a unitary nature and comprises a rigid annular base 9 which is U-shaped in cross section and which is somewhat wider than the felly upon which it is secured by means of radial bolts 10. The relatively greater width of the member 9 in comparison with the felly 3 facilitates the sliding adjustment of the clencher rings 4 and 5 upon the base of the member 9, affording extended bearing surfaces upon which these clencher rings are adapted to move.

At determinate intervals, there are mounted, in the channel of the member 9, rubber blocks 11 which extend radially and are surrounded by collapsible box-like formations individually comprising two pairs of hinges 12 and a joining plate 13 at their outer ends. At their inner ends, these hinges, or inner leaves of these hinges are provided with lateral extensions 14 (shown best in Fig. 3) which limit the tendency of the hinge leaves to assume a position of alinement and which in fact preclude the assumption of such position. The plate 13 bears upon the upper end of the rubber block which its box-like formation incloses. Thus, it is apparent that the plates 13 are fulcrumed upon the rubber blocks 11. The hinges 12 are independently collapsible. Stated in another way, each hinge of the box-like structure is independently yieldable toward the felly 3. The out-

ward movement of these hinge plates 13 is limited by the lateral extensions 14, as previously stated. 90

Each end of the plate 13 is pivotally connected to a tread section 15 and preferably this connection is detachable, at least at one end as at 16 in Fig. 3 where the pivot pin is shown to be removable, being a screw bolt. The tread sections 15 may be of any form but are preferably of the cross section shown in Fig. 2 so that the inner surface of the non-metallic shoe will not be lacerated by any sharp edges or corners.

In operation, it is found that the tread sections when forced inwardly yield independently, being in some instances entirely resisted in such yielding action by one rubber block or other equivalent and in some instances being resisted by a pair of these rubber blocks. The connection of the adjacent ends of the tread sections is such that

the depression of one section is practically not effective upon the other section to cause it to yield and yet the yielding section is resisted by at least one and probably two of 5 the rubber blocks utilized. The outward movement of the tread sections is positively limited by the lateral formation upon the bases of the hinges and consequently the collapsible box-like formation is never permitted 10 to become entirely extended and it therefore results that there can never be any rigid resistance caused by the alinement of the hinged sections. The function seems to be novel as a result of the combination afforded 15 by a single tread member with a yieldable support at either end and by the adjacent ends of tread members having a single yieldable support. This function is still further notable because the yielding of one of the 20 sections will exert a pressure upon the adjacent section to cause it to move away from the felly. However, such movement is prevented by the lateral extensions upon the bases of the hinges. This tendency is caused 25 by the manner of mounting the plates upon the rubber blocks. The plate acts upon the principle of the lever fulcrumed at its center, the movement of one end of the lever tending to cause movement of the other end 30 in the opposite direction about the fulcrum; when the lateral extensions are effective, the plate acts upon the principle of the lever fulcrumed at its end, a resistance at its center, and a movement of force at its fulcrumed end which is in the opposite direction 35 to the applied force at its free end. The result of this structure is that when a tread section yields, the adjacent end of the adjacent tread section will be more rigidly supported than under normal conditions. Stated in another way, if one tread section 40 received a severe shock or blow from a stone or other obstruction in the road, the adjacent tread section will be additionally prepared to assume its share of the shock. The action of the clamping rings has been explained and will be apparent.

Having thus described my invention what I claim is:

50. 1. In a resilient wheel, a felly, an annular member comprising tread sections, plates joining said tread sections, and resilient means mounted upon said felly to support said plates, said plates being positioned inward of the tread surfaces of said tread sections.
55. 2. In a resilient wheel, a felly, an annular member comprising tread sections, plates joining said tread sections, resilient means between said plates and said felly, and hinge members arranged in pairs about each of said resilient means.
60. 3. In a resilient wheel, a felly and an annular member comprising tread sections, resilient members supporting said sections,

hinge members connecting said sections to said felly, and lateral extensions on the inner ends of said hinge members to limit their movement.

4. In a resilient wheel, a wheel body, an 70 annular member comprising tread sections, hinges connecting said sections to said wheel body, and means to limit the movement of said hinges.

5. In a resilient wheel, a wheel body, an 75 annular member comprising tread sections, resilient means to support said tread sections, hinge members to connect the ends of each of said sections to said wheel body, and means to prevent alinement of the members of each of said hinge members.

6. In a resilient wheel, a wheel body, an annular member comprising tread sections, resilient means to support said tread sections, and hinges to join both ends of said 85 tread sections to said wheel body.

7. In a resilient wheel, a tread member comprising tread sections connected together, resilient supports positioned at the ends of each of said sections, said sections 90 being yieldable substantially independent of each other, and hinge members upon which said tread sections yield.

8. A resilient wheel comprising a wheel body, a plurality of tread sections, yieldable 95 box-like sections to join such tread sections together and to the wheel body, and resilient means to support said box-like sections.

9. In a resilient wheel, the combination of a wheel body, a unitary member comprising 100 tread sections disposed about said wheel body, and yieldable box-like formations to connect said tread sections to the wheel body, the two sides of said box-like formations being collapsible independently of each other. 105

10. A resilient wheel comprising a wheel body, a plurality of tread sections, and yieldable box-like sections to join such tread sections together and to the wheel body.

11. A resilient wheel, which comprises a 110 wheel body, a plurality of tread sections and yieldable box-like elements, one side of each of said box-like elements joining two adjacent tread sections, two sides of each box-like element being independently collapsible and joining the tread sections to the wheel body which is the fourth side of said box-like element. 115

12. A resilient wheel, which comprises a wheel body, a plurality of tread sections, and 120 a yieldable box-like element connecting each two adjacent tread sections to the wheel body and to each other, said box-like elements being constructed to permit one tread section to yield toward the wheel body without influencing the adjacent section to yield toward the wheel body. 125

13. In a resilient wheel, a felly, an annular member comprising tread sections, resilient means positioned between said mem- 130

ber and felly to support adjacent ends of tread sections, and links connecting said adjacent ends of tread sections, said links positioned upon said means so that movement 5 of one tread section toward said felly will tend to cause the adjacent tread section to move away from said felly.

14. In a resilient wheel, a felly, an annular member comprising tread sections, re- 10 silent means positioned between said mem-

ber and felly to support adjacent ends of tread sections, and links connecting adjacent ends of tread sections, said links positioned to oscillate upon said resilient means.

In testimony whereof I hereby affix my 15 signature in presence of two witnesses.

SAMUEL CLAY BARR.
